United States Patent Office

Des. 205,686
Patented Sept. 6, 1966

205,686

PLASTIC CAN

Paul A. Marchant, Kansas City, Mo., assignor to Rexall
Drug and Chemical Company, Los Angeles, Calif., a
corporation of Delaware

Filed Sept. 8, 1964, Ser. No. 31,626

Term of patent 14 years

(Cl. D58—17)

FIG.1

FIG.2

FIG.4

FIG.3

FIG. 1 is a perspective view of a plastic can showing my new design;

FIG. 2 is a side elevational view thereof;

FIG. 3 is the top plan view thereof; and

FIG. 4 is a fragmentary cross section taken on line IV—IV of FIG. 2 shown broken away for convenience of illustration.

I claim:

The ornamental design for a plastic can, as shown.
